(57) CLAIM

The ornamental design for a mirror, as shown and described.

DESCRIPTION

FIG. 1 is a left front perspective view of a mirror showing my new design;

FIG. 2 is a side elevational view, the opposite side being a mirror image thereof; and,

FIG. 3 is a front elevational view thereof.

The views of the mirror not shown form no part of the claimed design.

1 Claim, 3 Drawing Sheets

FIG. 1

FIG. 2

FIG. 3
